TEXTILE FABRIC

Herman Schwartz, Long Beach, N. Y.

Application April 19, 1955, Serial No. 35,582

Term of patent 3½ years

(Cl. D92—1)

The figure is a plan view of a textile fabric made in accordance with my design.

As viewed in the drawing, the upper and lower edges constitute the side edges of a length of textile fabric embodying my design. My said design extends longitudinally of the textile fabric, that is, from left to right as viewed in the drawing. My said design occupies a major part of the textile fabric which embodies it, leaving relatively narrow solid color side borders as represented by the upper and lower portions of the drawing.

I claim:

The ornamental design for a textile fabric, substantially as shown and described.
